(57) **CLAIM**

We claim the ornamental design for a device skin, as shown and described.

DESCRIPTION

FIG. 1 is a back perspective view of a device skin;
 FIG. 2 is a front perspective view of the device skin;
 FIG. 3 is a back elevational view thereof;
 FIG. 4 is a front elevational view thereof;
 FIG. 5 is a right elevational view thereof;
 FIG. 6 is a left elevational view thereof;
 FIG. 7 is a top plan view thereof; and,
 FIG. 8 is a bottom plan view thereof.
 The broken lines in FIG. 5 indicate portions of the device skin that form no part of the claimed design.
